RADIO TUNER CARTRIDGE FOR A TAPE- RECODER OR SIMILAR ARTICLE

Tetsujiro Hasegawa, 19-4 Nakacho, 2-chome,
Meguro-ku, Tokyo, Japan

Filed July 26, 1967, Ser. No. 8,013

Term of patent 14 years

(Cl. D26—14)

FIG. 1

FIG. 2

FIG. 1 is a front perspective view of a radio tuner cartridge for a tape recorder or similar article, showing my new design;

FIG. 2 is perspective view from the rear and bottom.

The dominant features of my design reside in the portions shown in full lines.

I claim:

The ornamental design for a radio tuner cartridge for a tape-recorder or similar article, substantially as shown and described.
